MACHINE FOR BLAST CLEANING WITH
GRIT SUCH ARTICLES AS CASTINGS

Ernest F. Fisher, Meredith, N. H.

Application June 12, 1946, Serial No. 676,271

6 Claims. (Cl. 51—14)

1

This invention involves a new and improved method and apparatus for blast cleaning castings and other objects with sand or metallic shot or grit which are impelled at high velocity to impinge on the surface of the castings thus removing scale and moulding sand.

According to this invention a stream of sand or metallic shot or grit merges with a high velocity air stream and attains the same velocity as the air stream. This high velocity mixture of air and gritty particles is directed against the surfaces of the castings and loosens the sand and scale therefrom. The spent particles of grit are collected and put back in the air stream for re-use, while the fine dust arising from the operation and the spent air are exhausted from the apparatus and conducted to a dust collector.

The invention will be further described in connection with the accompanying drawings in which Figure 1 is a vertical cross section taken on line 1—1 of Figure 2. Figure 2 is a horizontal cross section taken on line 2—2 of Figure 1. Figure 3 is a vertical section showing blower 12 which supplies the high velocity air for projecting the stream of grit that flows through tube 6 into the orifice of nozzle 16. Figure 4 is a vertical section of another form of blower.

Referring now to these drawings, the apparatus of Figures 1 to 3 comprises an enclosure or casing 1 which, with hinged hopper 2 forms a reasonably air tight enclosure for the castings to be cleaned. Within this enclosure is ram 3 which is designed to be raised and lowered in a reciprocating fashion by means of the revolving pinions 4 and the cooperating racks 5 which are attached to ram 3. This reciprocating vertical motion of the ram is affected by suitable reversing and limit switches controlling a motor (not shown) for driving shaft 4a.

Ram 3 is guided in casing 1 by liners 7 which afford clearances between the ram and the walls of the enclosure for the spent grit to drop down into conveyor trough 8. This spent grit is conveyed by the spiral conveyor 9 into elevator 10 which elevates the grit so that it will flow into separator 10a to be cleaned. The refuse is discharged through spout 11 and the cleaned grit flows by gravity through flexible tube 6a and connecting tube 6 into nozzle 16 of blower 12.

The hopper 2 which is hinged to the main casing 1 at point H serves several purposes. It serves as a door for casing 1. It serves as a spillway for the castings as they roll off the inclined top of ram 3. It serves to convey the

2

castings from the floor to the upper part of casing 1 or in other words, to load the machine. The hopper 2 is raised and lowered by the winch 17.

5 In operation, castings are placed in hopper 2 when it is in a lowered position as shown in dotted lines. It is then raised by the winch 17 and latched in position and the castings discharge into casing 1 dropping on ram 3 in its lowermost position as shown. The ram 3 is started reciprocating slowly up and down while the blower 12 discharges the air stream mixed with grit onto the castings as they rise upward and spill off the inclined top of ram 3 into hopper 2. As the ram descends the castings roll off hopper 2 back onto ram 3. This repeated up and down motion of the ram turns the castings over and over thus presenting all surfaces of the castings to the blast of air and grit.

10 The spent grit drops down through the clearances between ram 3 and the walls of casing 1 into trough 8 where the grit is conveyed by spiral conveyor 9 to the elevator 10 which elevates the grit to separator 10a where it is cleaned, the refuse passing out through spout 11 and the cleaned grit flows by gravity down tube 6 into the orifice of nozzle 16 of blower 12. The dust laden air is exhausted from casing 1 through opening 18 which connects with an exhaust fan which maintains a slight negative pressure within the apparatus to prevent dust from dissipating into the room.

15 After the castings are cleaned the ram 3 is raised to its topmost position or limit of travel upward and the castings spilled into hopper 2 which is then lowered to the floor by winch 17, thus completing the operation of cleaning.

The method of propelling the grit is shown in 20 Figure 3. The grit is fed through tube 6 to the orifice of the blower discharge nozzle 16 and does not come in contact with any part of the blower housing or impeller. Thus there is no erosion of the parts. Sufficient velocity is imparted to the air by the impeller 19 to give the grit a velocity of approximately 28,000 feet per minute which is sufficient to produce a good job of cleaning.

25 Any type of pressure blower can be used for supplying the necessary air for propelling the grit. The nozzle 16 can be swung back and forth about the axis 20 through an arc sufficient to cover any blast area in casing 1 so that all castings are reached by the blast. This nozzle can be separate and distinct from the blower as in 30 Figure 4. The blower in Figure 4 discharges the

air into nozzle 16 which swings through an arc on the trunnions 21 one of which fits over the discharge outlet of the blower. A flexible hose 6a is attached to tube 6 so that nozzle 16 can be swung freely through an arc sufficient to reach all the castings with the requisite blast.

I claim as my invention:

1. A blast cleaning machine comprising, in combination, a vertical casing to contain material to be cleaned, the upper portion of said casing having an inwardly sloping side provided with an opening therein, a loading and unloading hopper attached to said casing and also adapted to form a closure for said opening, means to raise and lower said hopper, a vertically reciprocating ram for tumbling said material within said casing, the top of said ram being inclined downwardly toward said hopper, means to direct a high velocity stream of air and grit against said material to be cleaned, and means to reciprocate said ram.

2. A blast cleaning machine comprising, in combination, a vertical casing to contain material to be cleaned, the upper portion of said casing having an inwardly sloping side provided with an opening therein, a loading and unloading hopper attached to said casing and also adapted to form a closure for said opening, a vertically reciprocating ram for tumbling said material within said casing, the top of said ram being downwardly inclined toward said hopper, means to reciprocate said ram, the upper limit of movement of the top of said ram being above the lower edge of said opening, means to direct a high velocity stream of air and grit against said material to be cleaned, and means to raise and lower said hopper.

3. A blast cleaning machine comprising, in combination, a vertical casing to contain material to be cleaned, the upper portion of said casing having an inwardly sloping side provided with an opening therein, a loading and unloading hopper attached to said casing and also adapted to form a closure for said opening, a vertically reciprocating ram for tumbling said material within said casing, the top of said ram being downwardly inclined toward said hopper, means to reciprocate said ram, the upper limit of movement of the top of said ram being above the lower edge of said opening, the lower limit of movement of said ram being below the lower edge of said opening, means to direct a high velocity stream of air and grit against said ma-

terial to be cleaned, and means to raise and lower said hopper.

4. A blast cleaning machine comprising, in combination, a vertical casing to contain material to be cleaned, the upper portion of said casing having an inwardly sloping side provided with an opening therein, a loading and unloading hopper attached to said casing and also adapted to form a closure for said opening, means to raise and lower said hopper, a vertically reciprocating ram for tumbling said material within said casing, the top of said ram being inclined downwardly toward said hopper, nozzle means swingable back and forth for directing a high velocity stream of air and grit against said material to be cleaned, and means to reciprocate said ram.

5. A blast cleaning machine comprising, in combination, a vertical casing to contain material to be cleaned, the upper portion of said casing having an inwardly sloping side provided with an opening therein, a loading and unloading hopper attached to said casing and also adapted to form a closure for said opening, a vertically reciprocating ram for tumbling said material within said casing, the top of said ram being downwardly inclined toward said hopper, means to reciprocate said ram, the upper limit of movement of the top of said ram being above the lower edge of said opening, nozzle means swingable back and forth for directing a high velocity stream of air and grit against said material to be cleaned, and means to raise and lower said hopper.

6. A blast cleaning machine comprising, in combination, a vertical casing to contain material to be cleaned, the upper portion of said casing having an inwardly sloping side provided with an opening therein, a loading and unloading hopper attached to said casing and also adapted to form a closure for said opening, a vertically reciprocating ram for tumbling said material within said casing, the top of said ram being downwardly inclined toward said hopper, means to reciprocate said ram, the upper limit of movement of the top of said ram being above the lower edge of said opening, the lower limit of movement of said ram being below the lower edge of said opening, nozzle means swingable back and forth for directing a high velocity stream of air and grit against said material to be cleaned, and means to raise and lower said hopper.
